Des. 203,882
Patented Feb. 22, 1966

203,882

ZOOM MAGNIFIER

Paul A. Hoogesteger, Brighton, N.Y. (134 Commodore Parkway, Rochester, N.Y.), and Robert D. Jacobs, 2508 E. Lake Road, Livonia, N.Y.

Filed May 24, 1965, Ser. No. 85,418

Term of patent 14 years

(Cl. D57—1)

FIG. 1

FIG. 2

FIG. 1 is a perspective view of a zoom magnifier showing our new design; and

FIG. 2 is a bottom view of said magnifier.

The side not shown has substantially the same appearance as the side shown.

We claim:

The ornamental design for a zoom magnifier, substantially as shown and described.
